UNITED STATES PATENT OFFICE.

JOHN S. HAAS AND RICHARD BERNHARD, OF ALLENTOWN, PENNSYLVANIA, ASSIGNEES TO TRAYLOR ENGINEERING & MANUFACTURING COMPANY, OF ALLEN-
TOWN, PENNSYLVANIA, A CORPORATION OF DELAWARE.

SAFETY DEVICE FOR CRUSHERS.

Application filed May 27, 1926. Serial No. 112,173.

Our present invention relates to improvements in ore and rock crushers of the swing jaw type which usually comprise a swing jaw and toggles with a pitman for operating the same.

Such crushers require some protecting means which will serve to prevent damage to the parts when some practically unbreakable substance, such as "tramp" iron enters the space between the crushing jaws, which, without such protection, results in material and costly damage in the nature of fracture of the swing jaws, or breakage of the pitman or toggle levers, or the straining or rupture of the frame. The damage is largely due to the fact that there is a great inertia stored in the moving parts which are very heavy and when movement is suddenly checked by such unbreakable substance the weakest part must give way. Such sudden stoppage of the moving parts frequently exerts forces ten times greater than that required for breaking rock or ore.

The present invention aims to provide a safety device which will effectually prevent damage to the crusher parts under such circumstances, and this in the shape of simple and economical means which may be readily applied to or incorporated in the standard types of crushers.

The invention further aims to provide means which may be readily manipulated to place the crusher in readiness for operation after the safety device has operated to prevent breakage on encountering an obstacle beyond the capacity of the crusher.

Still another object is to provide a device of this character in which the maximum resistance point may be readily varied when desired and according to circumstances.

With these and other objects in view the invention includes the novel construction and arrangement and combination of parts hereinafter described, the nature and scope of our invention being set forth in and defined by the claims appended hereto.

What we at present consider the preferred embodiment of our invention is illustrated in the accompanying drawings in which—

Figure 1 is a longitudinal vertical section through a swing jaw crusher.

Fig. 2 is a section on line 2—2 of Fig. 1 partly broken away.

Fig. 3 is a view of a modification, and 55
Fig. 4 is a view of a further modification.

As this crusher is of the standard type and will be well understood by those skilled in the art from a mere inspection of the drawings, no attempt will be made herein 60 to describe it in detail.

It suffices to say that 1 and 2 are the fixed and swing jaws respectively, the latter being operated from the cam shaft 3 through the intermediary of the pitman 4 and toggle 65 links or levers 5.

According to our invention we interpose at some point in the press between a power thrust member and a thrust resisting or thrust actuated member, a punch which acts 70 against an imperforate plate or bar of such resistance to punching action as will enable the crusher to function normally, but which plate or bar, on the entry of a relatively unbreakable substance between the jaws, 75 will allow the punch to pass therethrough.

A convenient manner of incorporating this punch or plate is shown in Figs. 1 and 2, in which the rocker or cross head 6 of the pitman is bored or recessed to receive a 80 plunger 7 which plunger acts to apply pressure to the knee of the toggle through a pivot bar 5^a secured thereto.

The plunger is fitted with a punch 8 which may be held in place by a taper or 85 drive fit in a recess in the under side of the plunger.

The rocker or cross head 6 is provided with a steel die 9 having an opening 9^a which corresponds in size to the die and to opening 6^a and is aligned therewith due to the sliding fit of the plunger in the bore of the rocker.

The rocker is provided with a transverse passageway 6^b to receive a bar 10 of material adapted to resist the punching action of punch 8 up to the desired point of resistance, such as a bar or plate of mild steel, and it is normally locked in position by releasable means such as set screw 11. As old 100 scrap material may be used for the bar 10 the cost thereof is negligible.

When the bar 10 is in place as shown in Figs. 1 and 2, all the parts are kept in contact during the operation of the press by 105 the customary spring jack 12, and by the retracting springs 13 of the swing jaw 2.

When tramp iron has fallen into the crusher

and the machine is in motion, the punch passes through the safety bar and the slug that is punched out falls out of the pitman rocker. The toggles immediately drop and 5 the inner end of the front toggle immediately falls until the swing jaw 2 is arrested by and rests on the two adjustable stop screws 14 on each side of the crusher only one of which appears in the drawing at the left of 10 Fig. 2. The pitman now continues to operate, but instead of lifting the toggles to move the jaw forward, it simply works up and down on the plunger 7, the punch passing through the hole perforated in the 15 safety bar. It will be seen that crushing immediately ceases because the clearance between the plunger and the pivot bar 5^a is greater than the total vertical stroke of the pitman.

20 The stops 14 (only one of which is shown) serve to prevent the toggles from dropping down beyond a limited distance so that the motion of the actuating device is less than the clearance of the mechanism after the 25 safety device has operated.

In order to commence crushing, it is necessary to stop the machine, take out the tramp iron, if same is still in the machine, and after the crusher has been cleaned, a jack is 30 used under the crusher to lift the toggles into closed position, the pitman being in its lowest position. A bar is then inserted underneath the punch, and punch and plunger are lifted and held in highest position. The 35 set screw 11 holding safety bar is then released and the bar is moved in either direction to present a new surface for punch.

The bar is then secured by the set screw 11 to prevent its moving. The jack holding 40 the toggle is then released to allow the punch to come in contact with the safety bar, and thereby support the plunger and toggles. The machine is then ready to operate. This change can be made in a very short time and 45 if a lifting jack for the toggles and wrenches is handy, the safety bar may be moved over in five minutes. It will be seen that the expense of maintaining the safety device is exceedingly low and the loss of time practically negligible.

While crushers may sometimes run for considerable time without encountering unbreakable substances, they may again receive such often and in some instances have 55 been known to do so several times in one hour. Hence an economical safety device such as disclosed, and one which after it has functioned, is of such a nature that the crusher can be readily restored to normal condition, is an extremely important factor.

It will be obvious that we do not limit ourselves to incorporating the punch in the pitman as disclosed in Figs. 1 and 2, as it may be placed in any position between a thrusting 60 and a thrust transmitting member. For ex-

ample, it may be placed between the main frame part 15 and the part or toggle block 16, which receives the thrust of the rear toggle arm as shown in Fig. 3.

In this form the safety punch 8^a is attached to or formed integral with the rear toggle block 16 and the abutting surfaces of the toggle block and frame part 15 are inclined relative to the line of thrust of the rear toggle arm so that the resultant upward pressure is resisted by the safety bar 10^a which in this instance is held in a passage-way in the overhanging part 15^a of the frame member 15 similar to that described in connection with Figs. 1 and 2, and the 80 stops 14 prevent the swing jaw from moving beyond the set distance when the safety bar is punched.

The punch of the toggle bar is kept in contact with the safety bar in normal operation by springs 17 acting on rods 18. When the bar is perforated the block 16 slides up, due to the action of the springs and is held in high position thereby preventing the toggles from acting on the swing jaw.

The arrangement shown in these last named figures is particularly applicable to the larger sized crushers where the toggle thrust is of greater magnitude and the jaw is of considerable dimension.

For smaller crushers having a narrower width of jaw, the punch 8^b may be placed on the rear toggle block 16^b in horizontal alignment with the line of thrust as shown in Fig. 4, and as the construction and operation of this will be readily apparent from this figure in the light of the foregoing specification, more specific description is deemed unnecessary.

Having thus described our invention, what we claim is:

1. In a safety device for crushers, having a fixed and a movable jaw, means for operating the movable jaw including a thrust member, and a thrust resisting member, a punch carried by one of said members, the other member having an eye aligned with said punch, a bar having an imperforate portion lying between said members and overlying said eye, and means for limiting the opening movement of the movable jaw.

2. In a safety device for crushers, having a fixed and a movable jaw, means for operating the movable jaw including a thrust member and a thrust resisting member, a punch carried by one of said members, the other member having an eye aligned with said punch, a bar having an imperforate portion lying between said members and overlying said eye, said bar being movably guided relative to said members to bring different portions in line with the punch, and means for limiting the opening movement of the movable jaw.

3. In a safety device for crushers, having

fixed and movable jaws, means for operating the movable jaw including a thrust member and a thrust resisting member, a punch carried by one of said members, the other member having an eye aligned with said punch, and a bar having an imperforate portion lying between said members and overlying said eye, said bar being movably guided relative to said members to bring different por-

tions in line with the punch, means for locking said bar against movement, and means for limiting the opening movement of the movable jaw.

In testimony whereof, we affix our signatures.

JOHN S. HAAS.
RICHARD BERNHARD.
